UNITED STATES PATENT OFFICE.

CHARLES C. WHITTAKER, OF WILKINSBURG, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,260,613.

Specification of Letters Patent. Patented Mar. 26, 1918.

Application filed March 4, 1916. Serial No. 82,163.

To all whom it may concern:

Be it known that I, CHARLES C. WHITTAKER, a citizen of the United States, and a resident of Wilkinsburg, in the county of 5 Allegheny and State of Pennsylvania, have invented a new and useful Improvement in Systems of Control, of which the following is a specification.

My invention relates to systems of control 10 for dynamo-electric machines and especially to systems that are adapted to control the operation of electric locomotives or other electrically-propelled vehicles.

One of the objects of my invention is to 15 provide a control system of the multiple-unit type for governing the operation of the driving motors of an electric locomotive that comprises two driving units, each of which may comprise one or more motors that are 20 disposed upon the locomotive trucks.

Another object of my invention is to provide a relatively simple system of the above-indicated type embodying means for arranging 25 the motor-circuit connections for different ranges of operating speeds, and also means for effecting alternate initial or starting operation of each of the driving motors prior to the remaining motors, whereby the heating of the motors caused by starting is 30 substantially equalized over an extended period of time.

A further object of my invention is to 35 provide a relatively simple and reliable mechanical interlocking device for two control drums, whereby one drum is alternately moved to a first and a second position each time the other drum is returned to its "off" position, as hereinafter more fully set forth.

During the operation of certain relatively 40 heavy-capacity locomotives of the type under consideration, more or less trouble has been experienced when hauling trains of relatively light weight or when switching around a train yard, in smashing knuckle pins or other portions of the train coupling and in "breaking trains in two", when starting, by reason of the fact that too much tractive effort is developed on the first notch of the motor controller, whereby all of the 45 motors are connected in circuit as is customary. Moreover, when liquid rheostats have been employed in connection with the motor acceleration, such undesirable results have been of greater severity, since, when the liquid is 50 at a low level in the rheostat tanks, the den-

sity of the solution is naturally greater and a relatively heavy current-surge occurs as a consequence. On the other hand, if the liquid density is reduced to provide the correct value of starting current when the minimum amount of liquid is in the rheostat tanks, an excessive surge of current is obtained at the end of the accelerating period when the rheostat short-circuiting switches are closed.

According to my present invention, I provide means for overcoming the above-mentioned difficulties comprising a special arrangement of the auxiliary governing circuit connections and a peculiar arrangement 60 and configuration of the contact segments of a governing controller, whereby only a certain portion, for example, one-half, of the driving motors or driving units shall be initially employed, and, therefore, only substantially one-half, or some other predetermined portion, of the total available mechanical energy or drawbar pull is initially utilized; the objectionable features just recited being thus completely obviated. In a 65 copending application of A. J. Hall, Serial No. 82,176, filed Mar. 4, 1916, and assigned to the Westinghouse Electric and Manufacturing Company, is set forth a system of the type just recited, wherein the same motor 70 or driving unit is always initially employed, thereby causing such motor or unit to assume a greater load than the other motors or units, with consequent injuriously high heating over an extended period of time. 75 In accordance with my present system, I alternately successively employ the several driving motors or units during the starting period, thus obtaining the desired results while maintaining substantially equal motor 80 or driving unit heating caused by starting.

In the accompanying drawings, Figure 1 is a view, in side elevation, of an electric locomotive comprising two driving units for the control of which my invention is adapted; Fig. 2 is a diagrammatic view of the complete main circuit connections and main control apparatus that is disposed upon the locomotive as shown in Fig. 1; Fig. 3 and Fig. 4 are diagrammatic views showing the 85 arrangement of motor-circuit connections for providing the desired ranges of operating speeds of the motors; Fig. 5 is a diagrammatic view of the auxiliary governing circuits for manipulating the various pieces 90 95 100 105 110

of main-circuit control apparatus that are shown in Fig. 2; and Fig. 6 is a view, in end elevation, of the control-drum interlocking mechanism that I employ in connection with my invention.

Referring to the drawings, the system shown is adapted for the control of one or more locomotives 1, the trucks 2 and 3 of which are respectively provided with driving motors or sets of motors M1 and M2. Obviously, the arrangement of motors with respect to the vehicle is relatively unimportant and my invention is equally applicable to locomotives comprising two half units of the illustrated type or to any other desired arrangement of driving-truck units or driving motors.

In Fig. 2, the system illustrated comprises a plurality of supply-circuit conductors 4, 5 and 6 which are adapted to deliver polyphase alternating-current energy to the polyphase induction driving motors M1 and M2; a plurality of sets of line switches A1, B1, and C1 and A2, B2 and C2 for respectively connecting the supply-circuit conductors 4, 5 and 6 to the motors M1 and M2; a pair of pole-change-over switches PCO#1 and PCO#2 for arranging the winding connections of the motors M1 and M2 for different numbers of poles; a plurality of liquid rheostats LR1 and LR2 that are respectively adapted to be connected in the secondary circuits of the motors M1 and M2 for governing the acceleration thereof; a plurality of operating mechanisms OM1 and OM2 for respectively actuating the rheostats LR1 and LR2; and a plurality of sets of switches X1 and Y1, and X2 and Y2 for respectively establishing short-circuit connections for the rheostats LR1 and LR2.

The motors M1 and M2 are preferably of the wound-rotor polyphase induction type and have suitable primary windings P1 and P2 and secondary windings S1 and S2, respectively. Initially, the windings are connected in delta relation and are adapted for a predetermined number of poles, for instance, 8 poles, while the windings may be connected in such manner as to halve the number of poles and thus produce machines of the four-pole type. No detailed description of the means for adapting the motors for different numbers of poles will be given, inasmuch as such connections are old and well-known in the art.

The pole-change-over switch PCO#1 comprises a group 7 of coöperating stationary and movable main contact members and a group 8 of coöperating stationary and movable interlocking or auxiliary contact members that are adapted to make coöperative engagement upon the position indicating lines 8P and 4P. The pole-change-over switch PCO#2 similarly comprises a group 9 of main contact members and a group 10

of auxiliary interlocking contact members that are also adapted for coöperative engagement on the corresponding position-indicating lines 8P and 4P. When the pole-change-over switches occupy their 8P positions, the windings of motors M1 and M2 are arranged for 8 poles while, in the 4P position, the change-over switches adapt the motor windings for 4 poles. A plurality of suitable electro-magnetic actuating devices 75 11 and 12 are preferably associated with the respective change-over switches.

By proper manipulation of the switches PCO#1 and PCO#2, the motors M1 and M2 may be initially connected in parallel relation, with 8 poles, as shown in Fig. 3, and subsequently in parallel relation, with 4 poles, as illustrated in Fig. 4, whereby the motors are adapted for two different ranges of operating speeds, for instance, from zero 85 to 14 MPH and from 14 to 28 MPH.

The liquid rheostats LR1 and LR2 may be of any suitable construction and, in general, severally comprise an electrolyte-containing tank or vessel 13; a plurality of suitably spaced plates or electrodes 14 that are adapted to be connected to the secondary induction motor windings through the pole-change-over switches; and a combined discharge and regulating valve 15, which is 95 adapted to regulate the height of the electrolyte in the tank 13, in accordance with a familiar practice. It will be understood that the particular type of liquid rheostat that is employed is immaterial to my present 100 invention and no further description thereof is believed to be necessary here, although, for a more complete exposition of the structure and operation of the preferred type of rheostats, reference may be had to a copending application of A. J. Hall, Serial No. 873,919, filed November 25, 1914, and assigned to the Westinghouse Electric and Manufacturing Company.

The operating mechanisms OM1 and OM2 110 for the valves 15 are of a well-known type and are shown as comprising a suitable fixed pulley wheel 20 around which is wound a rope or cable 21, one end of which is suitably associated with a rod 22 that is secured to the valve 15, and a suitable counterbalancing weight 23 is attached to the free end of the cable 21. The shaft of the pulley wheel 20 is provided with a pinion member 24 which engages a horizontally-movable 115 rack member 25 with the opposite ends of which a pair of pistons 26 and 27 are respectively associated to operate within suitable cylinders 28 and 29. A pair of valves 30 and 31 are respectively associated with the cylinders 28 and 29 and are adapted to admit fluid-pressure to the cylinders through a plurality of pipes or passages 32 and 33, respectively, from any suitable 125 source of fluid pressure (not shown), under 130

conditions to be set forth. The valves 30 and 31 are respectively provided with actuating coils On—1 and Off—1. The valve 30 is normally closed to exclude fluid pressure from the cylinder 28 and to connect the cylinder to the atmosphere, whereas, the other valve 31 is normally open to admit fluid-pressure to the cylinder 29 and to interrupt the communication of the cylinder 10 with the atmosphere, whereby the operating mechanism and the valve 15 are normally biased to the respective positions shown.

The rheostat LR1 is provided with an auxiliary or interlocking contact member LR1—up that becomes operative only when the rheostat is completely filled, and with a second contact member LR1—X that is operative except when the rheostat occupies its "flush - level" or substantially discharged 20 position, for purposes to be set forth. The contact member LR1—X is shown for illustrative purposes only, and the preferred structure embodies an oscillatable drum that is actuated by stops on the valve rod, as 25 fully described in a copending application of A. J. Hall, Serial No. 876,484, filed December 10, 1914, and assigned to the Westinghouse Electric and Manufacturing Company. The other rheostat LR2 is similarly 30 provided with auxiliary contact members.

To operate the mechanism OM1, the two actuating coils On—1 and Off—1 are simultaneously energized as set forth in detail in connection with Fig. 5, whereupon fluid-pressure is admitted to the cylinder 28 and is released from the cylinder 29, thereby effecting a movement of the pistons 26 and 27 toward the right, as shown in the drawing, and consequently, manipulating valve 15 to admit electrolyte to the tank 13. To arrest movement of the operating mechanism at any desired time, the coil Off—1 is deenergized, whereby balanced fluid-pressure conditions obtain in the two cylinders 40 and the desired stoppage is immediately effected. To return the mechanism to the normal position, it is merely necessary to deenergize both actuating coils, whereupon fluid-pressure conditions revert to the original state and the mechanism is actuated to the illustrated position. It will be understood without further description that the operating mechanism OM2 is similar in all respects to the operating mechanism OM1 50 being provided with actuating coils respectively marked On—2 and Off—2.

Reference may now be had to Fig. 5, wherein the auxiliary governing circuits shown comprise a master controller MC 60 having four independently-movable drums, a speed drum SD, an accelerating drum AD, a reversing drum RD, and an auxiliary drum marked "Rocker drum". The speed drum is adapted to successively assume an off position, a preliminary position *a*, an

initial running position A which corresponds to the completed main-circuit connections that are illustrated in Fig. 3, a transition position *b*, and a final running position B that corresponds to the completed 70 motor-circuit connection shown in Fig. 4. The accelerating drum AD is adapted to successively assume an off position and three positions respectively marked "Lower", "Hold" and "Raise", for suitably governing the operation of the mechanisms OM1 and OM2 of the several liquid rheostats. The rocker drum is adapted to occupy either of two positions *m*1 and *m*2 that respectively correspond to initial starting operation of 80 the motor M1 or the motor M2 prior to the other; and is mechanically associated with the other drums in the manner that is described in connection with Fig. 6.

In order to provide for multiple-unit train 85 operation, a plurality of train-line conductors TL are employed, in accordance with a familiar practice, and serve as intermediate conductors between the master controller drums, a suitable battery B, and the various actuating coils of the switching devices 90 that are illustrated in Fig. 2. In addition, a plurality of interlocking contact members that are either included in the groups 8 and 10 of the pole-change-over switches or 95 are associated with the line switches or the operating mechanisms, as shown in Fig. 2, are employed as about to be described in detail. It will be observed that the reversing drum RD forms a part of the master controller and that the usual actuating coils *r*' and *f*' of a familiar main-circuit reversing-switch RS are illustrated, although, for the sake of simplicity and clearness, the main-circuit reversing-switch RS is omitted 100 from Fig. 2. However, such a reversing switch is normally employed in connection with the operation of my system, as will be understood.

Assuming that the main and auxiliary 110 circuit connections are as illustrated, the operation of the system may be set forth as follows: The speed drum SD is moved to its initial or preliminary position *a*, while the accelerating drum AD may be moved to 115 its final operating position "Raise", whereby one circuit is completed from the positive terminal of the control battery B through conductor 40, train line conductor 41, conductors 42 and 64, control fingers 65 and 66 120 which are bridged by contact segment 67 of the accelerating drum AD in its position "Raise", conductor 68, train-line conductor 69, conductor 92, the actuating coil On—2, conductors 91 and 90, contact member 125 PCO #2—8P, conductors 89 and 88, train-line conductor 87, conductors 86 and 130, train-line conductor 131, conductor 132, contact member 133 of the rocker drum in its position *m*2, conductor 134, train-line con- 130

ductor 135, conductor 136, control fingers 137 and 78, which are bridged by contact segments 79^a and 79 of the speed drum SD, conductor 80, train-line conductor 62 and conductor 63 to the negative battery terminal.

10 A simultaneous circuit is established from the contact segment 67 of the accelerating drum AD through control finger 81, conductor 82, train-line conductor 83, conductor 93, and the actuating coil Off-2, whence circuit is completed through conductor 91 as just traced.

15 A further circuit is thereupon established from the positively-connected connector 42 through control fingers 43 and 44 which are bridged by contact segment 45 of the speed drum, conductor 46, train-line conductor 47, conductors 48 and 49 where the circuit divides, one branch under subsequent conditions including interlock LR1-X (not included in circuit at present), and the parallel-connected actuating coils of the switches A1, B1, and C1 and the other branch including conductor 49^a, interlock LR2-X and the parallel-connected actuating coils of the switches A2, B2, and C2, a common circuit being completed through conductors 50 and 51, contact member 52 of the main circuit reversing switch RS, conductor 53, train-line conductor 54, conductor 55, contact member 56 of the reverse drum RD in its forward position, conductor 57, control fingers 58 and 59 which are bridged by contact segment 60 of the speed-drum, and conductor 61 to the negative train-line conductor 62.

20 Upon the closure of the valves 30 and 31 of the operating mechanism OM2 and the closure of the line switches A2, B2 and C2, the motor M2 is gradually started into operation to effect the initial acceleration of the locomotive.

25 Upon movement of the speed drum to the initial running position A, another circuit is completed from the negatively-energized contact segment 79 of the drum through control finger 77, conductor 76, train-line conductor 75, conductors 74 and 73, interlock PCO#1-8P, conductors 72 and 71 and the parallel-related actuating coils On-1 and Off-1 which are respectively connected through conductors 70 and 84 to the train-line conductors 69 and 83 and thence to the control fingers 66 and 81 of the accelerating drum. In position A, the conductor 86 is also directly energized from the contact segment 79 through control finger 85, just prior to the disengagement of contact segment 79^a and control finger 137, thereby maintaining the energization of the actuating coils On-1 and Off-1, and open-circuiting the rocker drum connections for the remaining accelerating period.

30 Consequently, a predetermined time, de-

pendent upon the will of the operator, after the motor M2 is connected into circuit to effect initial acceleration of the train, the other motor M1 is brought into operation and thus full tractive effort is available a certain time after starting to accelerate the train to the speed that corresponds to running position A of the speed drum.

35 When the liquid in the rheostats LR2 and LR1 has reached its upper level, a circuit is established from the contact segment 67 of the accelerating drum through control finger 94, conductor 95, train-line conductor 96, conductor 97, the parallel-related actuating coils of the short-circuiting switches X2 and Y2, conductor 101, interlock LR2-up, and thence through conductor 90 to the negative battery terminal, as hereinbefore set forth. The short-circuiting switches of the liquid rheostat LR2 are thus closed, and a similar closure of the switches X1 and Y1 occurs by reason of the completion of a circuit from conductor 97 through conductor 98, the parallel-connected actuating coils of the switches X1 and Y1, conductor 99 and interlock LR1-up to the negatively-connected conductor 72.

40 To effect further operation of the system by transition of the motor-winding connections to the 4-pole arrangement that is illustrated in Fig. 4, the speed drum SD may be next actuated to its intermediate or transition position b, whereupon, at first, contact segment 79 is disengaged from contact finger 85, thereby deenergizing the circuits of the actuating coils of the short-circuiting switches X2, Y2 and also the actuating coils On-2 and Off-2 of the operating mechanism OM2, thus effecting the return movement of the operating mechanism, which, in turn, effects the deenergization of the actuating coils of the primary switches A2, B2 and C2 by reason of the exclusion from the governing circuits of the last-mentioned switches of the interlock LR2-X.

45 When the speed drum SD reaches its transition position b, a circuit is established from the contact segment 79 through control finger 116, conductor 117, train-line conductor 118, conductors 119 and 120, interlock B2-out, conductor 121, the actuating coil 4P of the pole-change-over switch PCO#2, interlock 122 thereof in the position 8P, and thence through conductor 97 to the positive terminal of the battery B, in accordance with a circuit that has already been traced.

50 The pole-change-over switch PCO#2 is thus actuated to its 4P position to correspondingly re-arrange the motor winding connections, and a governing circuit is thereupon completed from the conductor 119 through contact member PCO#2-4P, conductor 91, and the actuating coils On-2 and Off-2 of the operating mechanism OM2 130

provided that the accelerating drum AD occupies its position "Raise" to complete the energizing circuits that have previously been described.

- 6 When the transition of connections of the motor M2 has been effected, the speed drum SD may be actuated to its final position B, whereupon at first the contact segment 79 becomes disengaged from the control finger 70
- 10 77, and, as a result, the coils of the short-circuiting switches X1 and Y1 and the actuating coils On—1 and Off—1 of the operating mechanism OM1 are deenergized to permit a return movement of the liquid rheostat 75
- 15 LR1 to its discharged position. The return of the rheostat to such position effects an interruption of the circuit of the actuating coils of the switch A1, B1 and C1 by breaking the connection of the conductor 49 with 80
- 20 the actuating coils by reason of the exclusion of the interlock LR1—X. 85

When the speed drum SD reaches its final position B, a circuit is completed from the contact segment 79 through control finger 25 110, conductor 111, train-line conductor 112, conductors 113, and 114, interlock B1—out, conductor 115, the actuation coil 4P of the pole change-over switch PCO#1, contact member 116^a thereof in the position 8P, 90

30 and thence through conductor 97, as previously set forth. The other motor M1 is thus changed over to the 4-pole arrangement. The above-described successive transition of the motors from one set of connections that 95

35 corresponds to a certain speed to another set of connections that corresponds to a higher speed forms no part of my present invention and is fully shown and described and claimed in a copending application of 100

40 A. J. Hall, Serial No. 861,767, filed September 15, 1914, and assigned to the Westinghouse Electric and Manufacturing Company.

It will be understood without further 45 extended description that upon the energization of the actuating coils Off—1 and Off—2, the corresponding interlock members LR1—X and LR2—X again respectively complete the circuits of the primary switches 110

50 A1, B1 and C1 and A2, B2 and C2, the level of the electrolyte in the respective liquid rheostats is gradually raised in accordance with the operation of the mechanisms OM1 and OM2 and the various short-circuiting switches are again closed as soon 115

55 as the liquid rheostats occupy their completely-filled position. When the accelerating drum is returned to its off position, in readiness for the next accelerating operation 120

60 of the motors, the rocker drum is automatically moved to its position m1, as set forth in connection with Fig. 6. Consequently, when acceleration is again begun, with the speed drum occupying initial position a, a circuit 125

65 is established from the positive battery ter-

70 minal through actuating coils On—1 and Off—1 to conductor 76 as previously traced, whence circuit is continued through conductor 140, train-line conductor 141, conductor 142, contact member 133 of the rocker drum in position m1, and thence through conductor 134 to the negative battery terminal, as hereinbefore described. The motor M1 is thus initially energized, while the formerly initially energized motor M2 is not 75 operative until contact segment 79 engages control finger 85 in position A of the speed drum. Without further description, it will be understood that the motors M1 and M2 are initially brought into operation in that 80 order, which is the reverse of the order described in connection with the former acceleration, the operation subsequent to position A being identical with that previously set forth, since the rocker drum becomes inactive when contact segment 79^a breaks contact with control finger 137, as hereinbefore mentioned. Before the next acceleration, the rocker drum is automatically returned to position m2, as described below, and thus 90 the initial order of operation of the motors is reversed for each accelerating period. 85

To further control the operation of the liquid rheostats during acceleration of the motors, the accelerating drum may be moved 95 to its intermediate position "Hold," thereby deenergizing the coils Off—1 and Off—2 and thus arresting the movement of the operating mechanisms OM1 and OM2, as previously described; and the electrolyte levels 100 may be lowered at any time by moving the drum AD to its position "Lower" to thus deenergize both the "off" and the "on" actuating coils, as is familiar practice.

It will be observed that I have thus provided a relatively simple and reliable control system for initially effecting alternately successive operation of the number of driving units in an electric vehicle, whereby the motor heating caused by starting is substantially equalized over an extended period of time, and moreover, the previously mentioned undesirable operating results are entirely obviated. 105

Referring now to Fig. 6, the structure 115 shown comprises a cam member 145 that is rigidly secured to the shaft 146 of the accelerating drum AD and is provided with a projection 147 that assumes the illustrated position when the accelerating drum occupies its "off" position. A rod 151 is adapted to reciprocate within a stationary sleeve or collar member 152 and is normally biased to the position shown by a suitable helical spring 153 which operates between the collar 152 and a flange member 154 that constitutes the free end of the rod 151 and is adapted to be engaged by the cam member 145. A relatively thin flexible strip 155 of steel or other suitable material is rigidly as- 120

125 130

sociated with the other end of the rod 151 and loosely engages a notched member 156 that is rigidly secured to the shaft 157 of the rocker drum, which, for convenience, may 5 be loosely mounted, as a whole, upon the shaft of the speed drum SD. The member 156 has a pair of notches 158 and 159 that respectively correspond to the positions m_1 and m_2 of the rocker drum.

10 Assuming that the rocker drum occupies the illustrated position m_2 , and that the accelerating drum AD occupies the illustrated "off" position, the operating mechanical interrelation of the accelerating drum and the 15 rocker drum may be set forth as follows: When the accelerating drum AD is moved from its off position to any of the operative positions, the projection 147 of the cam 145 moves toward the dotted-line position that 20 corresponds to the "raise" position of the drum, whereupon the spring 153 actuates the flange 154 of the rod 151 toward the dotted-line position whereby the strip 155 passes from the notch 159 to an intermediate horizontal 25 position that lies opposite a portion of the other notch 158 of the notched member 156. Consequently, upon the return of the accelerating drum AD to its illustrated off position, the projection 147 forces the 30 rod 151 toward the notched member 156 in opposition to the action of the spring 153, and the flexible strip 155 engages the notch 158 and thereby actuates the rocker drum to the other position m_1 . Upon subsequent actuation of the accelerating drum to its operative positions and the return thereof to the off position, the rocker drum is again actuated to the position that is shown in the drawing, and thus the rocker drum alternately occupies its two positions in accordance with the actuation of the accelerating drum AD. Inasmuch as the accelerating drum is normally returned to its off position only when the accelerating period is 45 completed, it will be understood that the mechanical operation of the illustrated structure is such as to alternately effect the energization of the different driving units and thus substantially equalize the heating of 50 the motors over an extended period of time.

Obviously, various modifications of the circuit connections, structural features and location and arrangement of parts may be effected without departing from the spirit 55 and scope of my invention and I desire, therefore, that only such limitations shall be imposed as are indicated in the appended claims.

I claim as my invention:

60 1. In a system of control, the combination with a supply circuit, a plurality of motors adapted to receive energy therefrom, and means for arranging the connections of said motors for different ranges of operating speeds, of means for initially alternately

effecting operation of certain sets of said motors prior to the remaining motors.

2. In a system of control, the combination with a supply circuit, a plurality of motors adapted to receive energy therefrom, 70 and means for arranging the connections of said motors for different ranges of operating speeds, of means for successively connecting said motors in circuit during the initial accelerating period alternately in a 75 certain order and in the reverse order, whereby the motor starting loads over an extended period of time are substantially equalized.

3. In a system of control, the combination with a supply circuit, a plurality of motors adapted to receive energy therefrom and means for arranging the connections of said motors for different ranges of operating speeds, of means for initially alternately 80 employing one half and the remaining half of said motors, whereby the motor heating caused by starting is substantially equalized over an extended period of time.

4. In a system of control, the combination with a supply circuit, a plurality of polyphase induction motors adapted to drive a common load and to receive energy from said supply circuit, and switching means for arranging the connections of said motors 95 for different ranges of operating speeds, of means for effecting alternately successive initial operation of said motors.

5. In a system of control, the combination with a supply circuit, a plurality of polyphase induction motors adapted to drive a common load and to receive energy from said supply circuit, and switching means for arranging the connections of said motors for operation with different numbers of poles, 100 of means for effecting alternately successive initial operation of said motors.

6. In a system of control, the combination with a supply circuit, a plurality of polyphase induction motors adapted to drive a 110 common load and to receive energy from said supply circuit, and switching means for arranging the connections of said motors for different ranges of operating speeds, of controllable electrically-governed means for 115 controlling the operation of said switching means and for causing the switching means of each motor to alternately effect initial accelerating operation thereof prior to the operation of the other motor.

7. In a system of control, the combination with a supply circuit, a plurality of polyphase induction motors adapted to drive a common load and to receive energy from said supply circuit, and switching means for 125 arranging the connections of said motors for different ranges of operating speeds, of electrical means for controlling the operation of said switching means and comprising a master controller adapted to occupy a plu- 130

rality of operating positions and to initially effect alternately successive accelerating operation of said motors.

8. In a system of control, the combination with a supply circuit, a plurality of polyphase induction motors adapted to drive a common load and to receive energy from said supply circuit, and switching means for arranging the connections of said motors for 10 different ranges of operating speeds, of electrical means for controlling the operation of said means and comprising a master controller adapted to occupy a plurality of operating positions and having a plurality of 15 conducting segments for respectively governing the operation of said motors, said segments being arranged to effect the successive initial accelerating operation of said motors, and means associated with said segments for effecting an alternation of the successive operation thereof.

9. In a system of control for an electric vehicle having a pair of driving units, the combination with a motor for each unit, and 25 means for arranging the motor connections for different ranges of operating speeds, of means for effecting alternate initial driving operation of each unit prior to operation of the other.

10. In a system of control for an electric vehicle having a pair of driving units, the combination with a polyphase induction motor for each unit, and means for changing the number of poles of said motors to 35 obtain a plurality of ranges of operating speeds, of means for effecting alternately successive initial accelerating operation of said units, whereby substantially only one-half of the available driving energy is utilized at first and the motor heating caused by starting is substantially equalized over an 40 extended period of time.

11. In a system of control for an electric vehicle having a pair of driving units, the 45 combination with a driving motor for each unit, separate means associated with each

motor for changing the motor connections for different ranges of operating speeds, and separate means associated with each motor for governing the acceleration thereof for 50 each range of speed, of electrical remote-control means for governing the speed-changing means and the acceleration-governing means for each motor and embodying a controller for effecting concurrent operation of both of said acceleration-governing means, a second controller for effecting successive initial accelerating operation of said motors, and a third controller associated with said second controller for effecting an 55 alternation of said successive operations.

12. In a system of control, the combination with a supply circuit, a plurality of polyphase induction motors adapted to drive a common load and to receive energy from 60 said supply circuit, and switching means for arranging the connections of said motors for different ranges of operating speeds, of electrical means for controlling the operation of said means and comprising a master controller embodying one drum adapted to occupy a plurality of speed-changing positions and having a plurality of sets of conducting segments for respectively governing the operation of said motors, a second drum 70 for concurrently governing the acceleration of the motors, an auxiliary drum electrically associated with said segments, and mechanical interlocking means disposed intermediate said second drum and said auxiliary 75 drum for alternately effecting forward and reversed movements of the auxiliary drum each time the second drum is returned to its "off" position, whereby the said sets of conducting segments are alternately initially 80 energized to effect alternate starting operation of the motors.

In testimony whereof, I have hereunto subscribed my name this 29th day of Feb., 1916.

CHARLES C. WHITTAKER.
